United States Patent Office.

BRADFORD G. H. HATHAWAY, OF ROCK STREAM, NEW YORK.

Letters Patent No. 74,685, dated February 18, 1868.

IMPROVEMENT IN HARVESTERS.

The Schedule referred to in these Letters Patent and making part of the same.

TO ALL WHOM IT MAY CONCERN:

Be it known that I, BRADFORD G. H. HATHAWAY, of Rock Stream, in the county of Yates, and State of New York, have invented a new and useful Improvement in Harvesters; and I do hereby declare that the following is a full, clear, and exact description of the same, reference being had to the annexed drawings, making part of this specification, in which—

Figure 1 is a perspective view.

Figure 2 is a top view.

Figure 3 is a top view of the shoe.

Figure 4 is a vertical longitudinal section through the slide on the shoe, on the line xx , fig. 2.

Figure 5, another device for securing the cutter-bar.

Figure 6, a side elevation of lever for adjusting the height of the cut.

Figure 7, an elevation of the shifting-lever.

Figure 8, a section through the seat and spherical case.

Figure 9, a side elevation of the driving-bevel wheel.

Figure 10, an elevation of the opposite side of the same wheel.

Figure 11, an elevation of the planet-wheels and radial arms.

Figure 12, an elevation of the opposite side of the same.

Figure 13, a section through the spherical case.

Figure 14, a transverse section through the spherical case and shifting-mechanism.

Figure 15, a section through the hub of the driving-wheel.

Figure 16 is a perspective view of the pawl.

Figure 17, a section through the collar, showing the ratchet.

Figure 18, a front elevation of the hub and collar.

Figure 19, an elevation of the outer shoe.

Figure 20, a transverse section of the driving-mechanism; and

Figure 21 is perspective view of the stirrup for suspending the platform.

The same letters are employed in all the figures for the indication of the same parts.

These improvements relate to the harvester described in Letters Patent issued to me on the 28th day of May, A. D. 1867.

The nature of the improvements will appear from the following specification and claims.

Reference is made to the said original Letters Patent for a description of such parts as may be common to both, and which are fully described therein.

A A¹ are the wheels, of which the former is the driving-wheel. These wheels run on a revolving axle, B. C is the tongue. D, a spherical case enclosing the mechanism for driving the cutters. E, the driver's seat. F is a pawl in a recess of the hub of the driving-wheel, working into a ratchet in the recess in the collar F', fastened to the axle, the purpose being to turn the axle only when the driving-wheel is moving forward. These parts are all set forth in the original patent. A clutch, G, is attached to and revolves with the axle, but so attached that it may slide longitudinally on the axle, to throw the cutting-mechanism into or out of gear. This is done by a yoke, G¹, fitted into a groove around the clutch. The stem of this yoke extends through the spherical case, and is attached to a lever, G², which is pivoted to the hub of the case. G³ is a bell-crank, pivoted by lugs to the lever G², having an arm, G⁴, with a notch on it, which, entering a hole through the case, may be used for holding the clutch in gear, being pressed downwards by a spring, G⁵, placed behind the bell-crank. When the clutch is drawn back by the lever, the cutting-mechanism will not be operated. It may be put in motion by pressing forward the clutch until it connects with a corresponding clutch on the hub of the radial arms H, shown at H'. These radial arms turn on or with the axle, accordingly as they are engaged or disengaged by the clutch G. On their outer ends they carry the three planet-wheels I, which revolve on wrists projecting from the sides of the radial arms. These planet-wheels revolving with the arms are caused to turn upon their respective axes by the internal gearing D¹, placed on the inside of the spherical case D. They com-

minute motion to the spur-pinion K', cast on the back of the bevel-wheel K, which, turning on the axle, gives motion to the bevel-pinion L, on the shaft L¹, which, extending through the tubular attachment D² of the case D, carries the driving-crank L³. The pitman M, attached to the crank, drives the knives N', on the finger-bar N. The shoe and tongue are attached to the tubular extension D² of the case, all of which is set forth in said original Letters Patent, as is also the arrangement of parts for adjusting the height of the cut.

The following arrangement of parts is intended to allow the finger-bar to be folded back parallel with the machine: O is the shoe, resting on a wheel, O¹, and hinged to wrists on the braces, at O² O³. O³ is a cap, covering the end of the finger-bar N, which is made to turn back in a horizontal plane on a bolt passing through the cap, shoe, and finger-bar. The connecting-rod M is attached to a slide, M', running on guides formed in the cap O³, to which is fastened the cutter-bar N'. The end of the finger-bar is rounded, and has a notch to receive the point P¹, extending from a spring, P, fastened to the side of the shoe. This point holds the cutter-bar firmly in place. It may be detached by means of the cord or chain P³ and lever P⁴, when the cutter-bar may be folded back against the wheel, swinging in a horizontal plane. Q is a lever, with a hook at one end to project under the brace, the other end bearing against the cutter-bar. This projecting point prevents the shoe and cutter-bar from turning vertically when the cutter-bar is extended, but, as the finger-bar turns, the lever is forced back, disengaging the point, so that, when the finger-bar has been turned back parallel with the wheel, the shoe may be turned on its pivots, and the points of the fingers turned upwards, thus placing them in convenient position for shipping the machine, or moving it when not at work.

Instead of the spring P, I propose to use a dog, shown at x in fig. 5, having a shoulder fitting against a corresponding shoulder on the end of the finger-bar. The dog is attached directly to the shoe by a bolt, or by bending the end to pass through the shoe and form a pivot.

The stirrup S', fig. 21, is hung on the hub of the wheel A', which turns within it, and is used for suspending the rear of the platform when the machine is used as a reaper.

What I claim as my invention, and desire to secure by Letters Patent, is—

1. The arrangement of the sliding clutch G, yoke G¹, lever G², bell-crank G³, stem G⁴, spring G⁵, and spherical case D, substantially as described.
2. The combination of a shoe so attached as to oscillate laterally, and a finger-bar so hinged thereto that the shoe remaining stationary, the finger-bar may be folded back in a horizontal plane, to stand parallel with the line of draught, substantially as described.
3. The combination of the shoe O, hinged finger-bar N, spring P, or its equivalent, and lever Q, substantially as set forth.

In testimony whereof, I have signed my name to this specification in the presence of two subscribing witnesses.

B. G. H. HATHAWAY.
